REFRIGERATION APPARATUS

Le Roy F. Goines, Gastonia, N. C.

Application June 8, 1934, Serial No. 729,679

6 Claims. (Cl. 62—159)

This invention relates to a combined air connection and securing means for ice cans as employed in ice-making plants.

It is an object of this invention to provide a resilient means for securing ice cans in proper position in the brine tanks in the manufacture of ice, said resilient means being free from objections of rust formations and the like and being quickly removable to remove the ice cans as well as being quickly insertable for holding ice cans in proper position. Also, a quick detachable air connection is employed which is associated with a perforated pipe, said pipe being mounted for free swinging movement in the ice can during the freezing operation.

It is another object of this invention to provide means for securing ice cans in position in ice-making plants to prevent the increase in specific gravity of the brine from causing the cans to rise and in some instances cutting or closing the air connection.

Furthermore, in devices heretofore employed for positively holding the ice can in position some resilient means have been used, which resilient means usually comprise spring tension devices and as these spring tension devices contain steel and as they are exposed to the brine, they quickly rust. It is a well known fact that one bit of rust in an ice can will ruin an entire block of ice, and it is therefore an object of this invention to provide positive and resilient securing means which are quickly detachable and which are free from rust.

Some of the objects of the invention having been stated, other objects will appear as the description proceeds when taken in connection with the accompanying drawings in which:—

Figure 1 is an isometric view with portions broken away of a portion of an ice-making apparatus equipped with my invention;

Figure 2 is a longitudinal sectional view through one of the ice cans and showing my invention associated therewith;

Figure 3 is a transverse sectional view through two adjacent ice cans and taken along line 3—3 in Figure 2;

Figure 4 is an enlarged top plan view of my fastening means and associated parts;

Figure 5 is an enlarged elevation of my fastening means and associated parts;

Figure 6 is a vertical sectional view taken along line 6—6 in Figure 4;

Figure 7 is a modified form, showing slight structural differences over Figure 6.

55 Referring more specifically to the drawings,

the numeral 10 indicates a suitable floor or platform supporting the ice-making apparatus and disposed on this floor is usually a sheet of cork 11 which has a water tight connection with the end wall 12 and the sidewall 13 of the vat in which the ice cans are adapted to be placed for the freezing operation. This vat has a plurality of transversely disposed partitions 14 and a plurality of longitudinal partitions 15, said partitions 15 being a mere frame work at the top of the vat and do not forbid circulation of the brine enclosed in the vat. Transverse members 15 have secured thereto suitable non-corrosive members 17 and 18 which are adapted to support in any suitable manner, such as by transverse bolts 19, the refrigerating pipes 20, these pipes being adapted to have suitable refrigerating fluid to pass therethrough for cooling the brine and performing the freezing operation.

Disposed on top of the sheet of cork 11 are the non-corrosive members such as wood 21 which support or limit the downward movement of ice cans 36.

Ice-making machinery has heretofore employed a plurality of air conducting pipes 22 connected to a suitable source of compressed air for supplying compressed air to the ice plant during the freezing operation. These pipes are tapped by a suitable nipple 23, there being one nipple for each ice can in the apparatus. To each of these nipples 23 I secure a suitable conducting member for the air such as a rubber hose 24.

This rubber hose has its other end connected to a fitting 25 which is tapered and is adapted to securely fit into a chamfered cavity in the upper end of a perforated tube 26 which is open at its lower end and has a plurality of perforations intermediate its ends. This tube 26 is adapted to have universal movement in a horizontal plane, by having a suitable ball or enlargement 28 thereon disposed above a suitable non-corrosive fitting such as bronze through which the pipe 26 projects.

The bronze or other non-corrosive fitting 29 is secured on top of a spring-like board or wooden member 30 which is usually composed of white oak, suitable oak wood, and in fact any type of wood which is bendable such as ash or hickory. The ends of this wooden member 30 have suitable non-corrosive metallic members 31 and 32 on 50 the ends thereof whose outer ends are serrated to engage the sidewalls 14 of the transverse partitions in the apparatus. These are usually made of wood though lead or other non-corrosive substances may be employed. The serrated ends of 55

members 31 and 32 usually penetrate the wooden partition 14 and since the member 30 is pressed downwardly, in its central portion there is a resiliency which causes the buoyancy of the ice can pressing against the end members 31 and 32 to embed the serrated ends in the sidewalls of the partition members 14. If it is desired, suitable thin non-corrosive guide members 34 and 35 may be secured to the partition members 14 to limit the upward movement of the member 31 providing its serrated ends should not embed themselves in the partition 14. The ice cans are designated by reference characters 36, there being an ice can for each of the retaining members 31.

In Figure 7 there is shown a slightly modified form wherein the perforated tube 26 extends substantially above the fitting 28 and has the rubber hose 24 connected directly thereto. Immediately below the rubber hose is an enlarged spherical portion 28a which is integral or secured to the perforated pipe 26. The structures are very similar except that in Figure 6 the hose 24 can be disconnected from the fitting 25 when the ice cans are removed from the perforated pipe 26, whereas, in Figure 7, the hose 24 is disconnected from the upper end of pipe 26 when the ice can is to be removed from the apparatus after the water therein has become frozen and the holding member 30 is to be removed to allow the ice can to be removed from the brine.

It will be noticed that this apparatus will be free from all objections such as rusting parts and that it holds the can resiliently in position and forces it downwardly against the supporting members 21. No resilient material is employed for holding the can in position embodying any materials on which rust can collect. The apparatus is easily manipulated and can be installed and disconnected by one hand of the operator. Furthermore, the air supply means can be quickly detached therefrom and again attached thereto, when the ice can is to be removed and the block of ice discharged therefrom or the can is to be filled with water to be frozen again and installed in the brine tank. It will also be noticed that this apparatus permits easy withdrawal of the ice cans from the brine because when the water is frozen into a solid block of ice, a perforated tube of course is frozen in the ice, and by pressing downwardly on the member 30, the member 30 along with the perforated pipe can be removed from engaging position with the partitions 14 of the tank. When the hose 24 is disconnected, the holding means and disconnected pipe can be removed from the brine along with the can containing the block of ice whereby the pipe can be melted out of the block of ice at a point removed from the brine vat thus preventing dilution and contamination in the brine vat.

In the drawings and specification there has been set forth a preferred embodiment of the invention, although specific terms are employed, they are used in a generic and descriptive sense only, and not for purposes of limitation, the scope of the invention being set forth in the appended claims.

I claim:

1. Means for securing ice cans in brine tanks

and supplying compressed air thereto comprising a flexible strip of wood having toothed members on its ends for engaging the sidewalls of the tank when the central portion is pressed downwardly to force the can downwardly and after the pressure has been relieved, an air supply pipe mounted in said strip for free swinging movement, a compressed air supply pipe and a flexible hose having one end connected to the compressed air supply pipe and having its other end detachably secured to the upper end of the air supply pipe.

2. Combined air connection and securing means means for ice cans comprising a brine tank having a plurality of spaces for the reception of ice cans, compressed air pipes disposed along the upper portion of the tank, flexible hose connections leading from the pipe, a resilient wooden member whose length is greater than the length of a compartment and being adapted to be depressed at its center to force the ice can into the brine and whose ends are adapted to engage the sidewalls and hold the can in depressed position, a perforated pipe swingably supported by said wooden member and being adapted to have the free end of a hose connection secured thereto.

3. Ice-making apparatus comprising a brine tank, compressed air pipes disposed along the upper portion of the tank, partition members dividing the tank into a plurality of compartments, ice cans adapted to be disposed in said compartments, a resilient board member longer than the length of a compartment for securing an ice can in a compartment, an air pipe swingably supported by the board member and depending into the ice can and a detachable hose connection between the upper end of the air pipe, and a compressed air pipe.

4. In ice-making apparatus, the combination of a brine tank, a freezing can, a pipe depending thereinto a compressed air conduit, a branch leading from the latter and detachably connected to the upper end of the pipe, a resilient board for swingably supporting the upper end of the pipe, said board having means on its ends for engaging the brine tank for securing the can against upward movement.

5. Means for holding ice cans in a brine tank and for supporting an air supply pipe comprising a board member longer than the length of the tank and having means on its ends for engaging the walls of the tank after its central portion is depressed and released and means carried by the board for swingably supporting the air supply pipe.

6. An ice-making apparatus comprising a vat with a solution therein, an ice can disposed in said vat, means for holding said can in position comprising an elongated resilient wooden member having its ends abutting the sidewalls of said vat and its lower surface engaging the top of said can, the overall length of said resilient member being greater than the face to face dimensions of the sidewalls of said vat to cause the central portion of the resilient member to arch and exert pressure upon the sidewalls, to hold the resilient member and can in the solution.

LE ROY F. GOINES.
